US0D1072070S

(12) **United States Design Patent** (10) **Patent No.:** **US D1,072,070 S**
(45) **Date of Patent:** **** Apr. 22, 2025**

(54) **ASSEMBLING TOY**

(71) Applicant: **People Co., Ltd.**, Tokyo (JP)

(72) Inventor: **Masato Kiribuchi**, Tokyo (JP)

(**) Term: **15 Years**

(21) Appl. No.: **29/866,157**

(22) Filed: **Aug. 31, 2022**

(30) **Foreign Application Priority Data**

Mar. 4, 2022 (JP) ..... 2022-004478 D

(51) **LOC (15) Cl.** **21-01**

(52) **U.S. Cl.**

USPC **D21/484**; D21/468

(58) **Field of Classification Search**

USPC D21/398, 404, 468, 471, 479, 484, 489,
D21/490, 491, 658

CPC A63H 33/26; A63H 33/046

See application file for complete search history.

(57) **CLAIM**

The ornamental design for an assembling toy as shown and described.

DESCRIPTION

FIG. 1 is a front view of an assembling toy of the present invention.

FIG. 2 is a rear view thereof.

FIG. 3 is a top plan view thereof.

FIG. 4 is a bottom plan view thereof.

FIG. 5 is a right side view thereof.

FIG. 6 is a left side view thereof.

FIG. 7 is a perspective view thereof.

FIG. 8 is a sectional view thereof taken along section line **8-8** of FIG. 1.

FIG. 9 is a sectional view thereof taken along section line **9-9** of FIG. 1; and,

FIG. 10 is a sectional view thereof taken along section line **10-10** of FIG. 5.

The features shown in broken lines are included to illustrate portions of the assembling toy and form no part of the claimed design.

1 Claim, 10 Drawing Sheets
